2,138,815

MASSAGE VIBRATOR

Pearl L. Eberly, Denver, Colo.

Application October 22, 1936, Serial No. 106,965
Renewed October 13, 1938

5 Claims. (Cl. 128—51)

This invention relates to a power driven massage device and has for its principal object the provision of a powerful, highly efficient mechanism which can be easily and conveniently manipulated for body massage purposes.

Another object of the invention is to position the device on the extremity of a flexible shaft so that it can be easily manipulated by the masseuse without requiring a heavy motor to be lifted and carried.

Another object of the invention is to provide a compound massage machine, that is one in which two plungers or vibrators will be arranged to always move in opposite directions to each other so as to deliver a double vibration and eliminate vibration of the massage head.

Other objects and advantages reside in the detail construction of the invention, which is designed for simplicity, economy, and efficiency. These will become more apparent from the following description.

In the following detailed description of the invention reference is had to the accompanying drawing which forms a part hereof. Like numerals refer to like parts in all views of the drawing and throughout the description.

In the drawing:—

Fig. 1 is a longitudinal section through the massage head, taken on the lines 1—1, Fig. 2.

Fig. 2 is a face view of the head, with a cover plate removed.

Fig. 3 illustrates the complete device ready for use.

The invention employs a head member 10 formed with a convenient handle 11. The handle portion 11 is tubular to receive a shaft 12 mounted in suitable ball bearings 13. The forward extremity of the shaft 12 carries two eccentrics 14 and 15, surrounded by suitable ball bearings 16. The eccentrics 14 and 15 are mounted in reciprocating members 17 and 18 respectively.

The reciprocating members 17 and 18 are similar to each other in size, shape, and weight. They reciprocate directly against each other in sliding contact, and are guided in a suitable guide groove 19 in the head member 10. The reciprocating members are held in place in the groove and on the eccentrics by means of a suitable cover plate 20 which completely covers the groove 19 and the extremity of the shaft 12.

The ball bearings 16 are mounted in elongated bearing openings 21 formed in the members 17 and 18. The vertical width of these openings snugly engages the bearings 16. The horizontal width thereof is sufficient to allow for the move-

ment due to the eccentricity of the eccentrics 14 and 15.

It can be readily seen that as the shaft 12 rotates, the members 17 and 18 will reciprocate, in opposite direction to each other, once for each revolution of the shaft. The lower extremities of the members 17 and 18 project below the head 10 to receive sections 22 of a suitable rubber massage cup. The sections 22 may be secured to the members 17 and 18 in any desired manner, such as by means of clamp screws 23.

It is preferred to form the members 22 so that the two together form a complete cup-shaped depression. In action, one side of the cup will rise while the other side falls to give a rapid rocking or vibrating motion, which has been found to be exceedingly effective for massage and therapeutic purposes.

The inner extremity of the shaft 12 rotates in a bushing 24, which preferably extends beyond the handle member 11 to receive a clamping nut 25 for attaching a flexible shaft housing 26. The housing 26 encloses a flexible driving shaft 27, as is usual in flexible shaft constructions. The extremity of the shaft housing 26 terminates in a flanged sleeve 28 having a tubular extremity 29 which extends within the bushing 24, to align the flexible shaft with the handle member 11.

The flexible shaft 27 terminates in a tongue or keyed coupling 30, which passes into the extremity of the shaft 12 and engages a keyway 31 therein to transmit the power from the shaft 27 to the shaft 12. A suitable oiler is provided, as shown in Fig. 1, for filling the space about the shaft 12 with lubricating oil.

The shaft 27 is driven from a suitable electric motor 33, preferably mounted upon a wheeled platform 34, which allows it to be positioned convenient for the operator.

It is desired to call attention to the fact that the usual massage vibrating head has but a single motion, the reaction of which vibrates the massage head almost as vigorously as it does the patient. In the present machine, however, the reaction of the plunger 17 is offset by the reaction of the plunger 18 and the action of the plunger 18 is similarly offset by the reaction of the plunger 17, so that there is very little vibration imparted to the head 10.

While a specific form of the improvement has been described and illustrated herein, it is desired to be understood that the same may be varied, within the scope of the appended claims, without departing from the spirit of the invention.

Having thus described the invention, what is

claimed and desired secured by Letters Patent
is:—

1. A massaging device comprising: a head; a handle member extending from said head; an operating shaft extending through said handle and into said head; an eccentric formed on said shaft within said head; and a reciprocating member actuated by said eccentric, there being a guide channel within said head for guiding said reciprocating member, a second eccentric formed on said shaft 180° from said first eccentric; a second reciprocating member mounted on said second eccentric in slidable contact with said first reciprocating member; and means for holding said members in said head.

2. A massaging device comprising: a head; a handle member extending from said head; an operating shaft extending through said handle and into said head; an eccentric formed on said shaft within said head; and a reciprocating member actuated by said eccentric, there being a guide channel within said head for guiding said reciprocating member, a second eccentric formed on said shaft 180° from said first eccentric; a second reciprocating member mounted on said second eccentric in slidable contact with said first reciprocating member; and a cover plate on said head for holding said members therein and for maintaining said members on said eccentrics.

30 3. A massaging device comprising: a head; a handle member extending from said head; an operating shaft extending from said head; an operating shaft extending through said handle and into said head; an eccentric formed on said
35 shaft within said head; and a reciprocating member actuated by said eccentric, there being a guide channel within said head for guiding said reciprocating member, a second eccentric formed on said shaft 180° from said first eccentric; a
40 second reciprocating member mounted on said

second eccentric in slidable contact with said first reciprocating member; and means for holding said members in said head; a massage member formed in two parts, each part being connected to one of said reciprocating members.

4. A massage device comprising: a head member; a grooved channel extending longitudinally of said head member; a pair of reciprocating members positioned against each other in said channel; an operating shaft extending from said head at right angles to said reciprocating members; and eccentrics formed on said operating shaft at said reciprocating members, the latter having elongated openings for receiving said eccentrics. 15 10

5. In a massaging device, a handle member; a head member at one extremity of said handle member extending at right angles to and to one side thereof, a longitudinally extending channel in said head member open to the face thereof, 20 said channel extending across the axis of said handle; a shaft extending through said handle; a pair of opposite eccentrics on said shaft within said channel; a first reciprocating member of a width to fill said channel lying in the bottom thereof and provided with an elongated opening 25 for the reception of the first eccentric; a second similar reciprocating member lying against said first reciprocating member in said channel and receiving the second eccentric; a cover plate 30 closing said channel and holding said reciprocating members therein and also serving to hold said reciprocating members on their eccentrics; said reciprocating members projecting beyond said head and said cover plate; and a massage cup formed in two halves, each half being connected to the projecting portion of one of said reciprocating members. 35
